(57) **CLAIM**

The ornamental design for a jewelry display, as shown and described.

DESCRIPTION

FIG. 1 is a top and side perspective view of a jewelry display showing my new design which is a mirror image of the opposite side thereof;

FIG. 2 is a top view thereof;

FIG. 3 is a side view thereof which is a mirror image of all of the sides thereof;

FIG. 4 is a top, side perspective view of a first alternative embodiment which is a mirror image of the opposite side thereof;

FIG. 5 is a top, side perspective view of a second alternative embodiment which is a mirror image of the opposite side thereof; and,

FIG. 6 is a top, side perspective view of a third alternate embodiment which is also a mirror image of the opposite side thereof.

The sides of FIGS. 4–6 are the same as FIG. 3 except for the height and width differences thereof.
